(57) CLAIM

I claim the ornamental design for a dress form, as shown and described.

DESCRIPTION

FIG. 1 is a perspective view of a dress form, showing my new design.

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a front perspective view showing the dress form partially open; and,

FIG. 8 is an enlarged view of the adjustor of the dress form. The broken line immediately adjacent the adjustor represents the bounds of the claims and all other broken lines are for illustrative purposes only. None of the broken lines form a part of the claimed design.
